UNITED STATES PATENT OFFICE.

EDMUND P. KINNE, OF ALLIANCE, OHIO, ASSIGNOR TO AMERICAN STEEL FOUNDRIES, OF NEW YORK, N. Y., A CORPORATION OF NEW JERSEY.

WEDGE-LOCK FOR COUPLINGS.

1,124,914.

Specification of Letters Patent.

Patented Jan. 12, 1915.

Application filed July 20, 1912. Serial No. 710,535.

To all whom it may concern:

Be it known that I, EDMUND P. KINNE, a citizen of the United States, and resident of Alliance, in the county of Stark and State of Ohio, have invented certain new and useful Improvements in Wedge-Locks for Couplers, of which the following is a specification.

My invention relates to car couplers and 10 has particular reference to a novel coupler lock and the mounting therefor within the coupler head.

In the operation of railway trains and particularly freight trains the couplers 15 joining the adjacent cars are given hard usage with the result that the working parts wear and become loose. The wear is most apparent in the coupler knuckle; that is, the hook which engages the hook of the 20 mating coupler. This wear appears in the pivot pin, the locking face of the knuckle, the lock and the locking face of the coupler. As this wear increases, the knuckle is allowed to open beyond normal lines to a certain extent. When this abnormal opening 25 reaches a certain point the coupler becomes unserviceable and must be discarded, this for the reason that there is a tendency for the coupler to become disconnected from 30 the mating coupler if the knuckle does not remain closed to its full extent. This is a frequent cause of trains becoming parted while in motion.

The present invention relates to a coupler 35 so arranged that this wear is automatically taken up.

Many wedge locks have been suggested in order to automatically compensate for wear in the moving parts. However, these 40 locks as a rule wedge between the contacting surfaces and makes the lock difficult of removal.

By my arrangement the lock is wedged internally; that is, it is formed of three 45 parts, the central part being adapted to separate the two outer parts and increase the transverse dimension of the lock. The parts are intended to be secured against transverse displacement but are adapted 50 for relative longitudinal movement. Thus in service the lock is a unitary block having no loose parts but is adapted to be expanded in order to take up any wear occurring 55 between the knuckle and the locking face of the coupler.

The invention will be more readily understood by reference to the drawings, wherein,

Figure 1 is a sectional plan view of a coupler constructed in accordance with my invention; Fig. 2 is a transverse section on the line 2—2 of Fig. 1; Fig. 3 is an end elevation of my novel lock; Fig. 4 is a side view thereof; Fig. 5 is a bottom plan view, and, Fig. 6 is a top plan view of one of the sections of the lock.

Referring more particularly to the drawings, it will be seen that the coupler which is of the Janney type, is composed of a shank 10, a coupler head 11, a knuckle 12, pivoted at 13, a knuckle opener 14, and a locking block 15 composed of three parts 16, 17, 18. The central part 16 contains an apertured lug 18, to which is connected a link 19, projecting through an opening in the top wall of the coupler. This central portion is provided with undercut grooves 20, 20, with which ribs or flanges 21, 21, on the parts 15, 17, coöperate. Thus when assembled the parts are prevented from transverse movement but are permitted relative longitudinal movement. In the part 16, a flange or shelf 22, as shown in Fig. 2, extends in the plane of the groove 20, and limits the travel of the part 16 relative to the parts 15, 17.

In order to prevent the separation of the 85 parts by extended vertical movement of the part 16, lugs 23, 23, are formed alongside of the grooves 20, and after the parts are assembled these lugs 23 are bent over into the plane of the ribs 21. In Figs. 3 and 4 90 the lugs are shown without having been bent over, whereas in Fig. 5 they are shown as in service.

On the contacting faces of the parts 15, 16, I prefer to provide serrations 24, in order that the tendency of the part 16 95 to creep upwardly may be overcome in service. A projection or flange 25, on the part 15, coöperates with a groove or cut-away portion 26 in the wall of the coupler and guides the lock in its vertical movement. In 100 the locked position the block rests upon seats 27, formed on the bottom wall of the coupler a space being left between the seats for the downward travel of the part 16 when necessary to compensate for wear in the parts. In Fig. 3 the parts are shown in full lines in their normal position and in dotted lines in 105 the position assumed under extreme wear. This view also shows the extent to which the lock may be expanded.

It will be obvious that modifications may be made in the structure herein disclosed and such modifications as are within the scope of my claims, I consider within the 5 spirit of my invention.

I claim:

1. In a car coupler, the combination of a coupler head, a knuckle pivoted therein, and a locking member, said locking member being composed of a plurality of interfitting parts, one of said parts being wedge-shaped to act on another thereof, substantially as described.
2. In a car coupler, the combination of a head, a knuckle pivoted therein, and a locking member, said locking member being composed of a plurality of interfitting, wedge-shaped parts, one of said parts being bodily movable with relation to the 10 other, substantially as described.
3. In a car coupler, the combination of a head, a knuckle pivoted therein, and a locking member, said member being composed of a plurality of interfitting parts, wedge-shaped with relation to each other, one of 15 said parts being movable to cause a gradual expansion of said locking member to take up wear, substantially as described.
4. In a car coupler, the combination of a head, a knuckle pivoted therein, and a locking member, said member being composed of outer members having vertical locking 20

faces and an interposed and interfitting wedge-shaped part, and a lifter connected to said interposed part, substantially as described.

5. A locking block for car couplers, composed of outer parts having ribs and an intermediate wedge-shaped part having grooves, said parts being held in operative 40 relation by coöperation of said ribs and grooves, substantially as described.

6. A locking block for car couplers, composed of outer parts having ribs and an intermediate wedge-shaped part having 45 grooves, said parts being held in operative relation by coöperation of said ribs and grooves, the contacting surfaces between two of said parts being serrated, substantially as described.

7. A locking block for car couplers, composed of outer parts having ribs and an intermediate wedge-shaped part having grooves, said parts being held in operative 50 relation by coöperation of said ribs and grooves, the contacting surfaces between two of said parts being serrated, and integral clips adapted to be bent over the ends of said ribs and grooves to prevent separation of the parts, substantially as described.

EDMUND P. KINNE.
